UNITED STATES PATENT OFFICE.

MANES E. FULD, OF BALTIMORE, MARYLAND.

DESIGN FOR A CURRENT-REGULATOR CASE.

SPECIFICATION forming part of Design No. 29,977, dated January 10, 1899.

Application filed December 5, 1898. Serial No. 698,381. Term of patent 14 years.

To all whom it may concern:

Be it known that I, MANES E. FULD, a citizen of the United States, residing at Baltimore city, in the State of Maryland, have invented and produced a new and original Design for a Current-Regulator Case; and I do hereby declare the following to be a full, clear, and exact description of the invention, such as will enable others skilled in the art to which it appertains to make and use the same.

This design relates to the configuration of a current-regulator case of the kind used with electrical apparatus designed particularly for medical purposes.

In the accompanying drawings, which illustrate my design, Figure 1 represents a perspective view of the upper side of the current-regulator case. Fig. 2 represents a side elevation, and Fig. 3 represents a perspective view of the under side thereof.

The essential features of my design are the circular disk having the surrounding flange integral therewith extending beyond the under side of the disk only, thus leaving the upper face of the disk a plane surface and forming a circular hollow chamber upon the under side thereof, the under surface of the said disk having thereon the central boss in the form of a truncated cone, the series of concentric annular grooves, and the roughened annular surfaces between said concentric grooves, the wedge-shaped radial raised portion and the wedge-shaped plane surfaces upon either side of said radial raised portion interrupting the said circular grooves and said annular surfaces, as shown in the accompanying drawings.

From the center of the upper surface of the disk a cylindrical stem extends axially and has an enlarged cylindrical head. From the center of said boss upon the under side of the disk a cylindrical projection extends, and through the surrounding flange are formed openings, as seen in Figs. 1 and 3.

1 represents the circular disk; 2, the surrounding flange, which is integral with the disk; 3, the cylindrical stem, having the enlarged head 4 upon the upper face of the disk; 5, the central boss, and 6 the cylindrical projection extending centrally from the under face of the disk; 7, a deep circular groove surrounding said central boss at a short distance therefrom; 8 and 9, shallow and narrow circular grooves in the under face of the disk concentric with said deep groove 7 and 55 with each other; 13, the annular roughened surfaces between said grooves; 10, the radial wedge-shaped raised portion, and 11 and 12, the wedge-shaped surfaces upon either side thereof, interrupting the continuity of the 60 shallow grooves 8 and 9 and the annular roughened surfaces 13, and 14 the axial openings through the flange 2.

What I claim is—

The design for a current-regulator case, 65 substantially as shown and described.

In testimony whereof I affix my signature in presence of two witnesses.

MANES E. FULD.
